Fig 6

FIG. 1 is a perspective view of the motorcycle fairing embodying the design;

FIG. 2 is a left side elevational view thereof to a reduced scale;

FIG. 3 is a right side elevational view thereof to a reduced scale;

FIG. 4 is a front elevational view thereof to a reduced scale;

FIG. 5 is a rear elevational view thereof to a reduced scale; and

FIG. 6 is a top plan view thereof to a reduced scale.

The fragmentary broken line representation of the motorcycle shown in FIGS. 2 and 3 is for illustrative purposes only and forms no part of the design.

This is a continuation-in-part of design application Ser. No. 561,548, filed Mar. 24, 1975.

I claim:

The ornamental design for the motorcycle fairing, as shown and described.
